J. B. DALBEY,
AUTOMATIC GENERATOR,
APPLICATION FILED NOV. 4, 1914.

1,167,680.

Patented Jan. 11, 1916.

UNITED STATES PATENT OFFICE.

JOEL BENJ. DALBEY, OF NEVADA, IOWA.

AUTOMATIC GENERATOR.

1,167,680.

Specification of Letters Patent. Patented Jan. 11, 1916.

Application filed November 4, 1914. Serial No. 870,317.

To all whom it may concern:

Be it known that I, JOEL BENJ. DALBEY, citizen of the United States, residing at Nevada, in the county of Story and State of Iowa, have invented a certain new and useful Automatic Generator, of which the following is a specification.

My invention relates to automatic generators.

10 An object of my invention is to provide a generator for lamps, stoves or the like, using fuels requiring generation of a type wherein the same operation for supplying fuel will ignite the fuel.

15 A further object is to provide in such a generator means for simultaneously supplying a certain predetermined amount of fuel at a certain point, and for supplying means for igniting the fuel at the same point.

20 My invention consists in the construction, arrangement and combination of the various parts of the device, whereby the objects contemplated are attained, as herein-after more fully set forth, pointed out in 25 my claims and illustrated in the accompanying drawings, in which:

Figure 1 shows a side elevation partly in section, of a generator embodying my invention. Fig. 2 shows a detail sectional view taken on the line 2—2 of Fig. 1. Fig. 3 shows a horizontal sectional view of the support and standard taken below the bottom of the upper fuel receptacle with the upper portion of the fuel receptacle fixture 35 removed, and Fig. 4 shows a detail sectional view of the fuel discharge tube, and the portion of the igniting means taken on the line 4—4 of Fig. 1.

30 In the accompanying drawings, which disclose an exemplification of my invention, I have shown my invention applied to a hanging lamp of the type burning gasoline or kerosene gas. It will be understood, however, that my generator may be used in a 45 stoves and the like.

In the accompanying drawings, I have used the reference numeral 10 to indicate generally the upright supporting member, or a lighting fixture, formed on the upper portion of which is a portion 11 designed to be secured to the ceiling or wall or other support. At the lower end of the member 10 is a burner, and other parts, which will be hereinafter referred to. 50 Spaced above the burner and the parts connected therewith, is a heat shield 12.

Mounted on the member 10, at a suitable point thereof, is a fuel receptacle 13, having a supply tube 14, on which is a cap 14^a. Below the receptacle 13 is a receptacle 15, 60 so shaped as to give symmetry to the lamp, and designed to receive the measuring receptacle. The receptacle 13, when the cap 14^a is in place is substantially air tight, except for the tube 17 extending downwardly 65 from the bottom of the receptacle 13.

A transverse shaft 18 is mounted in the walls of the member 15 and supports a measuring cup 19 in such a way as to permit the tilting of such cup. The cup is normally held in its retaining position by means of a spring 20. The parts are so arranged that the tube 17 extends downwardly into the cup 19, so that when the fuel in the receptacle 13 flows downwardly into the tube 70 17, in the cup 19 and reaches the lower end of the tube 17, a liquid seal is formed. Communicating with the interior of the member 15, extending downwardly therefrom, is a discharge tube 21. Mounted on 75 the lower end of the member 10 are suitable fuel tubes 22 for supplying fuel such as gasoline, and suitable tubes 23 for carrying the gas generated from such fuel to a burner 24 which may support a mantle 25, as illustrated in the drawing. Suitably mounted adjacent to the fuel supply tubes is a receptacle 26, preferably filled with suitable non-inflammable material 27 such as asbestos. The tube 21 is arranged to discharge into the 80 receptacle 26. Secured to the side of the interior of the receptacle 26 is a laterally extending spring wire 28. Suitably pivoted and insulated from the other parts is a lever 29, one end of which extends into 85 the receptacle 27, and the other end of which extends outwardly therefrom, as shown in Fig. 1. Fixed to the shaft 18 outside the member 15 is an arm 30 to which is secured a chain 31, which is insulated from 90 the arm 30. Chain 31 is secured to the outer end of the lever 29. Depending from the lever is a chain and ball 32 and 33. The parts hereinbefore described are of suitable 95 conducting material, so that when an electric circuit having the wire 34, forming part of the circuit, is connected with the upper portion of the member 10, current may be conducted to the wire 28. The other wire 35 of the circuit is suitably connected by 100 means of the collar 36, and wire 37 with the chain 31. In the circuit is a suitable source

of power 38, and preferably a suitable choke coil 39. It will be understood that the parts 36 and 37 are shown outside the members 13 and 15 for purposes of illustration, but that 5 they may be placed inside the members 13 and 15, giving the device a better appearance.

The spring 20 normally holds the outer end of the lever 29 in its raised position, 10 thereby holding the inner end of said lever out of engagement with the wire 28. If, however, the operator grasps the ball 23 and pulls the chain downwardly, the cup 19 is tilted to discharge its contents which must 15 flow downwardly through the member 15 and the discharge tube 21 to the receptacle 26, at the same time the outer end of the lever is lowered, and the inner end thereof is raised until said inner end engages the wire 28, closing the circuit. As the movement of 20 the lever 29 is continued, the inner end of said lever passes said wire 28, and when the lever 29 leaves the wire 28 an arc is formed, whereby the fuel is ignited from the tube 22, 25 for suitably generating the gasoline or the like in the tube 22. As soon as the operator releases the ball 23, the spring 20 returns the parts to their normal positions.

It will be understood that the cup 19 may 30 be made of such size and may be so arranged with relation to the tube 17, that the liquid fuel contained in the cup before each discharge will be just the proper required amount for properly generating the gasoline 35 or other fuel used by the lamp, stove, or other device as the case may be.

The advantages of such a device, as that herein described, whereby fuel capable of 40 easy ignitions may be supplied in predetermined amounts at a proper point for generating other fuel, and whereby a spark can be simultaneously applied to the first fuel in which the operative parts are actuated by a single movement of a single part are obvious.

It will be understood that numerous 50 changes may be made in the construction and arrangement of the parts of my device without departing from the spirit and purpose of my invention, and it is my intent to cover by this application any such changes which may be included within the scope of my claims.

I claim as my invention.

55 1. In a generating device of the class described, a support, a burner mounted thereon, a fuel receiver adjacent to said burner, a fuel supply tube adapted to lead to said receiver, a receptacle pivotally mounted and 60 adapted in one position of its movement to discharge into said tube, means for yieldingly holding said receptacle in horizontal position, a fuel supply tube adapted to extend downwardly into said receptacle when 65 the receptacle is in its horizontal position,

and means for tilting said receptacle and for simultaneously causing a spark at the discharge end of said first named tube.

2. In a device of the class described, a fuel receptacle, a movable receptacle mounted below said first receptacle, means for yieldingly holding said movable receptacle in horizontal position, a tube leading from said first receptacle and adapted to stand with its lower end received within the movable receptacle, when the latter is in horizontal position, a receptacle below said movable receptacle, a discharge tube leading from the receptacle below the movable receptacle, and means for tilting said movable receptacle for discharging its contents into said last described tube.

3. In a device of the class described, a lamp fixture comprising an upright member, a fuel receptacle mounted thereon, a movable receptacle mounted below said first receptacle, means for yieldingly holding said movable receptacle in horizontal position, a tube leading from said first receptacle and adapted to stand with its lower end received within the movable receptacle, when the latter is in horizontal position, a receptacle below said movable receptacle, a discharge tube leading from the receptacle below the movable receptacle, means for tilting said movable receptacle for discharging its contents into said last described tube, a burner on the lower portion of said support below said fuel receptacle, a fuel receiving device adjacent to said burner, and below the discharge end of said last described discharge tube.

4. In a device of the class described, a lamp fixture comprising an upright member, a fuel receptacle mounted thereon, a movable receptacle mounted below said first receptacle, means for yieldingly holding said movable receptacle in horizontal position, a tube leading from said first receptacle and adapted to stand with its lower end received within the movable receptacle, when the latter is in horizontal position, a receptacle below said movable receptacle, a discharge tube leading from the receptacle below the movable receptacle for discharging its contents into said last described tube, a burner on the lower portion of said support below said fuel receptacle, a fuel receiving device adjacent to said burner, and below the discharge end of said last described discharge tube, and means for tilting said movable receptacle, and for simultaneously igniting fuel discharged from the lower end of said last described tube.

5. In a device of the class described, a lamp fixture comprising an upright member, a fuel receptacle mounted thereon, a movable receptacle mounted below said first receptacle, means for yieldingly holding said movable receptacle in horizontal posi-

- tion, a tube leading from said first receptacle and adapted to stand with its lower end received within the movable receptacle, when the latter is in horizontal position, a receptacle below said movable receptacle, a discharge tube leading from the receptacle below the movable receptacle for discharging its contents into said last described tube, a burner on the lower portion of said 10 support below said fuel receptacle, a fuel receiving device adjacent to said burner, and below the discharge end of said last described discharge tube, means for tilting said movable receptacle, and for simultaneously igniting fuel discharged from the lower end of said last described tube, a fuel supply tube leading to said burner, a valve therein, and means for operatively connecting said valve with said first means.
- 15 6. In an automatic generator, a fuel receiver, a supply tube adapted to discharge into said receiver, means for supplying a predetermined amount of fuel to said supply tube, a lever pivoted adjacent to the discharge end of said tube, and having one end adapted to engage said tube in one position of the movement of said lever, an electric circuit including said lever and said discharge tube, means for connecting said lever with said first means, means for yieldingly holding said lever in one position of its movement, said parts being so arranged that when said lever is moved from such position, said first means is actuated and thereafter the parts of said lever moves to a position adjacent to said tube for causing a spark.
- 20 7. In an automatic generator, a fuel receiver, a supply tube adapted to discharge into said receiver, means for supplying a predetermined amount of fuel to said supply tube, a lever pivoted adjacent to the discharge end of said tube, and having one end adapted to engage said tube in one position of the movement of said lever, an electric circuit including said lever and said discharge tube, means for connecting said lever with said first means, means for yieldingly holding said lever in one position of its movement, said parts being so arranged that when said lever is moved from such position, said first means is actuated and thereafter the parts of said lever moves to a position adjacent to said tube for causing a spark.
